UNITED STATES PATENT OFFICE.

ISAAC FORREST OTTO, OF TANEYTOWN, MARYLAND.

FIRE-ESCAPE.

1,140,281.

Specification of Letters Patent. Patented May 18, 1915.

Application filed August 20, 1912. Serial No. 716,057.

To all whom it may concern:

Be it known that I, ISAAC FORREST OTTO, a citizen of the United States, residing at Taneytown, in the county of Carroll and 5 State of Maryland, have invented certain new and useful Improvements in Fire-Escapes; and I do hereby declare the following to be a full, clear, and exact description of the invention, such as will enable others skilled in 10 the art to which it appertains to make and use the same.

My invention relates to fire escapes of the folding ladder type and it consists of the provision in fire escapes of this class of 15 means for securing the folding member of the fire escape in inoperative position, said holding means serving also the purpose of a circuit closer of an electric alarm circuit, automatically operated when the ladder is 20 unfolded or brought to operative position.

With this object in view, the invention consists in the improved construction, arrangement and combination of the parts of a device of the character specified, which 25 will be hereinafter fully described, and afterward specifically claimed.

In order that the construction and operation thereof may be readily comprehended, I will now proceed to fully describe my invention in connection with the accompanying drawings, which illustrate an approved embodiment thereof, and in which drawings, 30

Figure 1 is a perspective view of my invention complete in position for use, Fig. 2 35 is a similar view showing my fire escape folded in compact and attractive form, Fig. 3 is a detail view showing my folding fire escape disposed in a compact and folded position and illustrating means for anchoring 40 the same to the wall or other support, Fig. 4 shows a similar view to that illustrated in Fig. 3 and showing my fire escape as in an unfolded condition, Fig. 5 is a detail view showing a section of my improved fire escape in a folded condition and illustrating portion of an electric circuit, Fig. 6 shows my ladder proper provided with clamping means which will hold it in an extended or unfolded condition, as will be desirable when 45 used as a ladder, and, Fig. 7 shows simple, though efficient, means for connecting two sections of my fire escape or ladder in permanent union with each other.

Like reference characters mark the same 50 parts wherever they appear in a plurality of the figures of the drawings.

Referring in detail to the drawings, 1 and 2 indicate two ladder uprights, each of which is in form substantially one-half of a tube longitudinally divided and said uprights 1 and 2 are pivotally connected together by a plurality of tread members or ladder rounds 3, shown in detail in Fig. 4, and formed of tubing of proper length engaged at each end on a suitable bolt or pin 60 tle 4 passing therethrough whereby the said sections may be readily brought together, the result being that the folded ladder will 65 present a tube-like appearance against the wall of the building. Suitable washers 5 may be interposed between the edges of the 70 uprights 1 and 2 and said rounds, whereby the said rounds will be held centrally disposed relative to said uprights 1 and 2.

The upright 1 is secured to the wall, preferably by hooks 6 anchored in the wall in any desired manner, as by means of heads or nuts 7. I prefer to form recesses in the edge of the upright 1, whereby the hooks will be 75 accommodated so as to present no obstruction to the contiguous edge of the upright 2, when the latter is folded against the upright 1.

To the upright 1, I secure at any preferred point thereon a plug or post 8 of 80 non-conducting material as of fiber or the like, and to said post I secure a pair of spring fingers 9, normally in contact with each other, but adapted to be separated by a post 10 of fiber, glass or other non-conducting material, carried by the upright 2 at a point thereon which will insure that the 85 said post 10 will readily enter between the outwardly curved ends of the spring fingers 9, and it is obvious therefore that, when 90 the uprights 1 and 2 are in contact with each other, as when the fire escape is folded, the said non-conducting post 10, will have entered between the spring fingers 9 so that said fingers will be held apart. 100 When my improved fire escape is in an unfolded or operative condition, the said fingers 9 will be withdrawn off the plug 10, thereby permitting said spring fingers to move into contact with each other, thus 105 completing an electric circuit through wires 11 attached to said fingers. Any number of bells or other alarms may be connected up in the electric circuit of the wires 11, and said wires may extend to different points 110 throughout the building.

Obviously, when my improved fire escape

is folded whereby the uprights 1 and 2 will be in contact with each other, the electric circuit will be broken, through the interposition of the non-conducting plug 10 between the spring members 9, but when the uprights 1 and 2 are separated, the plug 10 will have passed from between the fingers 9, thereby causing the bells or alarms in the electric circuit to ring continuously until the fire escape is again folded. The addition of my automatic alarm will be found very desirable to indicate any unauthorized use of the fire escape, as for instance, an attempt to enter the building in that way.

15 In addition to serving as a circuit closer, the spring fingers 9 in connection with the post 10, serve to retain the upright 2 in its folded or inoperative position, wherein, as before described, the circuit is broken by 20 the interposition of said plug between the fingers.

At a point opposite each window is a handle 12, and any person desiring to place the fire escape in condition for use may push 25 lightly outwardly upon said handle, with the hand or foot, causing the upright 2 to swing by gravity into its operative position, parallel with the upright 1, leaving the rounds 3 in a horizontal position ready for 30 instant use.

In Fig. 2 my improved folding fire escape presents the appearance, when folded, of an ordinary line of piping, which may be painted or otherwise protected or decorated.

35 In Fig. 6 I have shown my improved fire

escape divided into sections and employed as an ordinary ladder by providing braces 13 and 14 each having an elbow joint, whereby they may be folded out of the way when not in use. The sections 13 may be pivoted 40 on the pintle 4, which passes through the ladder rounds, the said brace 13 being extended through a suitable slot 15 in said round, as clearly shown in Fig. 6. In like manner the brace 14 is provided with a suitable hooked end to reach into a slot 16 in the lower side of the contiguous ladder round, into engagement with the pintle or bolt upon which said round is pivoted.

Having thus fully described my invention, 50 what I claim as new is:

In combination, a fire escape of the folding ladder type comprising, parallel upright members, a plurality of tread members pivoted at each end to, and connecting said upright members, adapted to permit of the collapsing of the ladder, and a plurality of brace members pivoted within one of said tread members each having a folding hook section hooked within the neighboring tread member to brace said device in open position.

In testimony whereof I have signed my name to this specification in the presence of two subscribing witnesses.

ISAAC FORREST OTTO.
